UNITED STATES PATENT OFFICE

160,351

CAMERA

Wallace W. Ward, Bloomfield, N. J., assignor to
Universal Camera Corporation, New York, N. Y.,
a corporation of New York

Application August 4, 1949, Serial No. 4,308

Term of patent 14 years

(Cl. D61—1)

To all whom it may concern:

Be it known that I, Wallace W. Ward, a citizen of the United States and a resident of Bloomfield, county of Essex, and State of New Jersey, have invented a new, original, and ornamental Design for a Camera, of which the following is a specification, reference being had to the accompanying drawing, forming part hereof, in which:

Fig. 1 is a side elevation of a camera, embodying my new design;

Fig. 2 is a front elevation of the same;

Fig. 3 is a side elevation opposing that of Fig. 1;

Fig. 4 is a rear elevation of the same; and

Fig. 5 is a plan view of the same with the view finder elements collapsed.

I claim:

The ornamental design for a camera, as shown and described.

WALLACE W. WARD.
